STAMP CANCELING AND MARKING MACHINE.

No. 896,366.

Specification of Letters Patent.

Patented Aug. 18, 1908.

Application filed November 7, 1907. Serial No. 401,183.

To all whom it may concern:

Be it known that SAMUEL J. EVANS, late deceased, did invent certain new and useful Improvements in Stamp Canceling and 5 Marking Machines, and that CELIA E. EVANS, of Roanoke, Virginia, administratrix, declares that the following is a specification thereof.

The invention relates to stamp canceling and marking machines, and it is the object of 10 the invention to provide a machine of simple construction and capable of rapid operation in the production of the work.

The invention includes a rotary marking head, normally inactive and controlled by 15 combined letter-registering stop and locking-key mechanism to register the letters and determine the times at which the rotary marking head will be set in operation.

The invention consists in the features and 20 combination and arrangement of parts hereinafter described and particularly pointed out in the claims.

In the accompanying drawings,—Figure 1 is a plan view of so much of the improved 25 stamp canceling and marking machine as is necessary to a complete understanding of the invention. Fig. 2 is a sectional view substantially on the line 2—2 of Fig. 1. Fig. 3 is a detail view of the rotary marking head 30 and devices associated therewith. Fig. 4 is a sectional view substantially on the line 4—4 of Fig. 1 and looking towards the left. Fig. 5 is a view of a marking head having two sets of marking elements and the letter registering and locking mechanism associated 35 therewith. Fig. 6 is a detail sectional view of means for adjusting the ink roller. Fig. 7 is a detail view of a detent. Fig. 8 is a bottom plan view of the cam associated with the 40 marking head. Fig. 9 is a view of a detail.

In these drawings, 1, 2, are a pair of rolls between which the letters pass initially, being guided thereto by any suitable means, such as the guide plates 3, 4. The roll 1 which is 45 the separating roll, is revolving in the direction of the arrow and backwardly in relation to the course which the letter must take in passing through the machine. The roll 2 rotates in a forward direction or opposite to 50 that of the roll 1, and any suitable gearing may be employed for giving these rolls the rotary movement in the desired direction. Such gearing is illustrated generally in Fig. 2 the shaft 5 of the roll 2 having a gear 6 thereon and the shaft of the roll 1 having a gear 7

thereon, these gears being connected through intermediate pinions 8. From the rolls 1, 2, the letters pass between another pair of delivery or timing rolls 9, 10, both rotating forwardly in the arrow directions and both of these rolls being positively driven through any suitable means to advance the letters to the letter-registering stop and locking-key mechanism which is located in advance of the rotary canceling and marking head, indicated generally at 11, this rotary canceling and marking head coöperating with a platen 12 between which and the marking head the letters pass to be marked and canceled. The letter-registering-stop and locking-key mechanism comprise a stop 13 having its end 14 arranged in the path of the letters as they pass between a pair of guide rolls 15, 16, arranged intermediate the rolls 9 and 10 and the marking head and platen. The end 14 of this letter-stop lever is slightly grooved on its face to receive the leading edge of the envelop. The stop is pivoted at 17, to a lever 18, which in turn is pivoted at 19 to a bracket 20 suitably supported on the frame 21. This lever is connected by a link 22 to a presser-rod or bolt 23, which slides in a housing 24 carried by the bracket 20. This presser bar or bolt is arranged to operate a releasing lever 25 by pressing upon its end said lever being pivoted at 26 to the rotary marking and canceling head, and this releasing lever in turn is adapted to operate a detent 27 which normally holds the rotary marking head against movement, for which purpose 23 the said detent engages a projection or catch 28, fixed rigidly to the marking head. The detent 27 is carried by a housing 29 pivotally supported at 30 on the bracket 20, the said detent being adapted to have slight longitudinal movement in the said housing and being under pressure from the spring 31 arranged in the said housing 29, this spring providing a cushion effect when the rotary head is arrested by its catch 28 striking the detent 27. 95

Normally the detent is held locked in engagement with the catch 28 to thus hold the rotary marking and canceling head against movement by means of a lock or locking-key 105 32. This locking-key is adapted to slide in the housing 24, before described, being under tension of a spring 33. It is guided by a stud or screw 34 passing through a slot 35 in the lock or locking-key 32. This lock is pro- 110

vided with a projection or locking point 36, which engages a corresponding projection or point 37 on the housing 29 of the detent or stop 27. The locking-key is connected with the lever 18, before described, by means of a pin 37' projecting from the said lever into a slot or notch 38 formed in the said locking-key.

With the parts in the position illustrated in Fig. 1, it will be noticed that the end 14 of the registering stop lies directly in the path of the oncoming letter as it enters the bite of the rolls 15 and 16. The shaft of the roller 15 is shown at 15' and both of these rollers lie in a higher plane than the registering-stop and locking-key mechanism above described.

With the parts in the position illustrated in Fig. 1, the registering stop is in position to contact with the leading edge of the envelop and at this time the rotary marking head is held stationary by the detent 27. As soon, however, as the envelop strikes the registering-stop 13, this stop is moved aside by the swinging action of the lever 18, due to the pressure from the letter on the registering-stop and the movement of this lever is imparted through the link 22 to the presser-bar 23, which thus presses upon and operates the releasing lever 25, carried by the rotary marking head, and as the movement of the lever 18 has retracted the locking-key 32 so as to withdraw the locking point 36 from the locking point 37 the swinging movement of the said releasing lever 25 will now be effective to throw the detent 27 out of engagement with the catch 28, and the rotary marking head may now freely rotate, carrying the canceling ribs 39 and the post-marking stamp 40 against the envelop so that the impression will be made, these ribs and stamp operating in conjunction with the platen 12, it being understood that ink has been applied to the said ribs and stamp through the means to be hereinafter described. The releasing lever 25 is returned to normal position after each operation by a spring 25'.

The rotary marking head is driven through a friction connection or clutch, this comprising a disk or ring of leather or like material 41 surrounding a part of the rotary marking head, this disk resting upon a rotary shaft or sleeve 42 which is constantly in rotation, being driven in any suitable manner, such for instance as through a coupling 43.

As soon as a letter passes the registering stop 13, this stop will be restored to position shown in Fig. 1, so that its end will lie across the path of the next envelop or letter, this action being due to the spring 44 bearing upon the end of the registering stop and the lever 18 and all the parts associated therewith will also be restored to their normal position shown at Fig. 1, by the action of a cam surface 18' on the rotary marking head operating against presser bar 23 and in resuming

this position the locking-key will, by its projection 36 working against the projection 37 of the housing 29, move this housing pivotally so that the detent 27 will be thrown towards the center of rotation of the marking head and thus lie in the path of the catch or projection 28 to contact therewith and arrest the rotary motion of the marking head until such time as the next letter is registered by means of the registering stop or key 13, and, as above explained, when the rotary head is arrested there is a slight cushioning effect afforded by the spring within the housing 29, acting on the detent 27 which is adapted to have slight longitudinal movement. A spring 24 presses the locking key towards its locking position. The rotary head is prevented from rebounding by means of a catch or detent 45 supported on a post 46, and adapted to engage in rear of the projection or catch 28 on the rotary marking head. The parts of the letter-registering-stop and locking-key mechanism having resumed their normal positions the detent will be held in engagement with the catch on the rotary head by means of the locking-key 32.

The rotary head turns with the stem or post 46, it having a sleeve extension 47 extending along the post. For steadyng the said post and the rotary marking head an arm 48 is provided extending from the post 46 and embracing the sleeve 47. A spring at 49 is provided to hold the release lever 25 in normal position.

After being marked and canceled the letter passes between rolls 50, 51, and thence to the stacker 52, this stacker being mounted to turn about the point 53 and consisting of a series of radiating arms carrying at their outer ends rollers 54. The purpose of these rollers is to properly direct the envelops and prevent them from doubling up or becoming damaged as they would otherwise be likely to do if the rollers were not employed. The rollers 1, 2, 10 and 16, the platen 12 and roller 51 is rubber covered and the bearing of most of these rollers are yieldingly supported, such for instance as illustrated in Fig. 2 where the bearing of the roller 1 is shown as adapted to slide in an opening 55 in the frame, it being pressed by means of a spring 56 in a housing 57, said spring surrounding a rod 58 connected with and pressing upon a collar 59 on the said rod. Substantially the same construction may be employed with the other bearings. The roll 50, however, is supported in a bracket 60 adapted to have sliding movement in a casing 61, it being pressed by a spring 62 in the casing and said casing being pivotally mounted at 63 to the main frame so that access may be had to the rotary marking head by swinging the casing 61 and with the bracket 60 to one side. When in proper position the casing together with the bracket 60 may be maintained in proper relation to 130

the roll 51 by a pin 64 passing through a part of the casing and into the frame 21. The post marking stamp 40 is removably held by the rotary marking head for which purpose said head is provided with a recess on its side into which the flanged base of the marking stamp is adapted to be dropped in place by gravity.

For inking the canceling ribs and post marking stamp an inking roller 65 is provided carried by a shaft 66, said roller having ink supplied thereto by a distributing roll 67 mounted upon a shaft 68, this shaft being driven in any suitable manner, as by the gearing 69 as shown in Fig. 4. Ink is supplied to the ink distributing roller 67 from a fountain 68 by means of an oscillating arm 69 carrying a pad 70 of fibrous material adapted to take up a quantity of ink and apply it to the ink distributing roll. The arm 69 is hung within the fountain by a pin 71 passing through a slot 72 in the said arm and it is operated by means of a pin 73 on a face plate or worm wheel 74 journaled within the fountain, and operated by a worm 75 on a shaft 76, which is driven through bevel gearing 77, 78, from the shaft 68 of the ink distributing roller. The pin 73 works within a loop or strap 79 of the arm 69 and this gives oscillatory movement to the said arm. The arm however, is pressed normally upwardly by a spring 79. Within the loop or strap is arranged a spring 80 to be borne upon by the pin 73 at the time that this pin is acting to press the arm towards the ink distributing roller, the pin and slot construction 71, 72 allowing longitudinal movement of the arm to press the inking pad against the roller and the spring 80 providing a cushion to take up any excess pressure from the pin 73. The worm 75 is connected with the shaft 76 by means of a clutch 81 operated by a lever 82, so that the inking mechanism may be thrown into or out of operation at will by simply operating this finger lever. An overflow at 83 is provided for the ink fountain, this consisting of an exterior receptacle connected with the interior of the ink fountain by an opening 84 at the lower part of the said fountain. From the receptacle 83 the ink passes to a cup shaped receiver 85, from which it may be drawn off through a valve 86.

The roller 2 is connected with its shaft by means of a pawl and ratchet mechanism, which pawl and ratchet, while acting to drive the roller to advance the envelop will permit the said roller to turn in the same direction ahead of its shaft so as to prevent damage to the envelops should the rolls 9 and 10 feed the envelops forward faster than would otherwise be allowed by the speed of rotation of the roller 2.

It will be understood that one important function of the rolls 9 and 10 which may be termed timing or delivery rolls is to insure

the same degree of impact of letters of all thickness or stiffness against the letter registering key or trip 13 so that said trip will be operated with the same degree of certainty and timeliness when a thin letter comes along as when a thick letter arrives at said trip or key.

It will be noticed that the letter registering stop is yieldingly mounted and that it has yielding movement laterally in respect to the side of the letter. Now when it is moved aside and the letter is passing it said registering stop rests against the side of the letter and should at this time, *i. e.*, while the stop is resting against the side of the letter, the cam on the marking head act to move the presser bar and lever 18 back to normal position the said letter registering stop will simply yield in respect to the said lever 18 and thus no extra pressure will be on the letter and all tendency of tearing said letter will be avoided, which would not be true were not the letter registering stop yieldingly arranged. This will allow the device to receive letters of various lengths.

Reverting to the action of the rotary marking head it will be understood from the above that said head is brought to rest between the marking actions and is held until released by the next oncoming letter striking the letter registering stop and it therefore becomes important to provide a marking head which will take care of the shortest letters however fast they are fed against the registering stop. The marking head is, for instance, two inches in diameter and its periphery is therefore roughly 6 inches and a fraction, and were this given a full revolution for each letter or marking action the timing or delivery rolls 9 and 10 would have to be reduced in speed so that the short letters would arrive at the letter registering stop at intervals corresponding to the full revolution of the marking head, otherwise said letters would buckle up, owing of course to the fact, that, the letter registering stop and its associated parts are returned and held against movement by the cam surface on the rotary marking head until said head has made its revolution and has brought the low part of said cam opposite the presser bar 23. In order therefore to increase the capacity of a machine of this character having an intermittently operating rotary marking head, on said head are provided two marking stamps at diametrically opposite points, two sets of canceling ribs, two cam surfaces, two catches and two releasing levers 25, all as shown in Fig. 5, so that a stamp canceling and post marking operation can be performed at each half revolution of the marking head.

Referring now to the inking mechanism, the inking roller 65 has its shaft 66 carried by a bearing bracket 65', which is pivotally connected or hinged at 66' to the inking fountain

frame 66^x. The purpose of this is to permit the inking roll to be adjusted towards the marking head when the fiber of said roll has been condensed or compressed to such an extent as not to contact properly therewith. The bracket or bearing for the shaft of the inking roll is therefore adjusted by means of a screw passing through a boss 67^z on the frame 66^x and bearing against a part of the bracket 65^z. This screw moves the bracket in one direction while a spring 67^y moves the bracket in the other direction. Of course when the bracket 65^z is adjusted to move the inking roller towards the distributing roll its position relative to the marking head is changed and it becomes necessary to adjust the bracket or frame of the inking mechanism as a whole and this is done by loosening the screws 69^z and moving the entire ink fountain with the shaft 68 and ink distributing roller 67 and the inking roller 65 towards the marking head and then the screws are again tightened to hold the parts in adjusted position. To permit the adjustment just described to take place the shaft 68 has a flexible portion therein consisting of the spring 69^x between the main shaft section 68 and the section 67^x to which latter the power is applied through the train of gearing shown in Fig. 4. Each shaft section has a forked portion as at 67^a, 67^b to receive the ends of the spring.

Means have been provided whereby the platen will accommodate itself automatically to different thicknesses of letters or to letters which are thicker at one point than at another or which contain substances or articles which make the surface of the letter uneven. For this purpose, as shown in Fig. 4, the platen shaft 88 has its bearings in a bracket 89 which is pivoted at 90 to a plunger 91, movable in a bracket 92 which is fixed to the frame of the machine. This plunger is pressed by a spring 93 to force the platen to its work and the tension of this spring may be varied by the screw 94 bearing on the spring, and which is held in position by the set nut 95. The bracket 89 of the platen is held in normal position against pivoting by a leaf spring 96 connected therewith and to the main frame at 97. This spring while holding the platen and its shaft normally upright will permit the said platen and its bracket to tilt on its pivot pin 90 in case a letter is passing between the platen and the marking head which is of uneven thickness and the result of this is that the letter although having an uneven surface will be so pressed that it will receive practically the full stamping or canceling mark thereon. To permit this tilting of the platen and its bracket, the shaft 88 is jointed at 98, and has a sliding connection at 99.

The friction drive of the marking head is provided with an adjustment whereby it is

possible to make this drive act on the instant the marking head is released from its holding means. This adjustment consists of a nut 41^x on the threaded end of the stem of shaft 46 of the marking head drive, said nut when turned serving to force the marking head downwardly against the friction driving disk. This nut may be turned by inserting a suitable pin in one of several openings 42^x in the nut, and when the parts are adjusted they may be held to their work by a set nut 42^y. A spring 43^x is interposed between the nut 41^x and the upper end of the sleeve or extension 47 to provide a yielding quality to the friction drive. By this means it will be clear that the friction drive may be so set as to impart rotary motion to the marking head at the instant the said marking head is released from its holding devices.

What is claimed as the invention is:

1. In combination in a machine of the class described, a rotary marking-head normally inactive, holding means therefor, a letter-registering-stop and locking-key mechanism, the said letter-registering-stop being actuated by contact with the letter and causing the operation of the locking-key to release the holding means, substantially as described.

2. In combination in a machine of the class described, a rotary marking-head normally inactive, a detent for holding the same, a locking device for the detent, releasing means for the detent, and a letter-registering-stop for operating the releasing means and the locking means, substantially as described.

3. In combination in a machine of the class described, a rotary marking head normally inactive, a detent for holding the said head, a release device carried by the said head for rendering the detent inactive, a letter-registering-stop and means operated thereby for operating the release device, substantially as described.

4. In combination in a machine of the class described, a normally inactive rotary marking-head, a detent for holding the said head, a releasing device for the detent to move it in inactive position, said releasing device being carried by the marking-head, a letter-registering-stop, a locking-key for the detent, a presser bar or plunger for operating the releasing device and a lever connected with the locking-key, and presser bar and operated by the movement of the letter-registering-stop, substantially as described.

5. In combination in a machine of the class described, a normally inactive rotary marking head, means for holding and releasing the same and a register stop arranged with its end face across the path of the letter and extending with its main part alongside and lengthwise of the path of the letter to its pivotal point, said stop being adapted to be

1. moved by the said letter and to one side of the path thereby, said registering stop controlling the holding means, substantially as described.
2. In combination with the rotary marking head, a detent mounted to yield in the direction of movement of the marking head in arresting the movement of said marking head to cushion the shock, a letter-registering-stop and means for controlling the said detent from the said stop, substantially as described.
3. In combination with a rotary marking head, a detent for arresting the same, a lever pivoted on the marking head for releasing the detent and a letter-registering-stop supported independent of the marking head and adapted to operate the said releasing lever, substantially as described.
4. In combination with a marking head, a detent for arresting its rotary movement, a letter-registering-stop supported independent of the marking head and means on the marking head controlled by said stop for releasing the detent, substantially as described.
5. In combination with a marking head, a letter registering stop, a connection controlled thereby for releasing the rotary marking head and means for returning the connection and letter registering stop to normal position, said stop being pivotally and yieldingly mounted in respect to said connection and extending from its pivotal point longitudinally of the path of the letters to allow the said connection to return to normal position while said stop remains in contact with the side of the passing letter, substantially as described.
6. In combination with a marking head, a letter registering stop, a connection controlled thereby for releasing the rotary marking head, rotary cam means for returning the connection and letter registering stop to normal position, said stop being yieldingly mounted in respect to said connection to allow the same to return to normal position while said stop remains in contact with the side of the passing letter, substantially as described.
7. In combination in a machine of the class described, a letter registering stop, means for feeding the letters thereto, a rotary marking head having a plurality of stops thereon, holding means therefor, for holding said head normally against movement, said holding means being released from the stops by the operation of the letter registering stop and a plurality of similar marking means on said head effecting in one revolution a plurality of marking actions, substantially as described.
8. In a stamp canceling machine, a marking head, a platen and means for supporting said platen to permit tilting thereof to assume positions in which its peripheral surface is at an angle to the peripheral surface of the marking head, so that said platen accommodates itself to letters of uneven thickness to make a marking impression over said uneven surface, substantially as described.
9. In combination in a letter marking machine, a marking head, a rotary platen, a pivot support for said platen, a jointed shaft for driving the platen and means for yieldingly holding the platen in normal position but to allow the same to tilt so that its axis will be at an angle to that of the marking head when letters of uneven thickness are passing, substantially as described.
10. In combination in a letter marking machine, a marking head, a rotary platen, a pivot support for said platen to allow it to assume angular positions axially in respect to the marking head, a spring for pressing the platen towards the marking head and a second spring for holding the platen in normal position against tilting, substantially as described.
11. In combination in a machine of the class described, a letter registering stop, means for feeding the letters thereto, a rotary marking head having a plurality of stops thereon, means to engage the said stops to hold the marking head against rotation, a plurality of releasing means on the marking head to operate the said holding means, and a plurality of similar marking means on the head effecting in one revolution a plurality of similar marking actions.
12. In combination with the marking head, a detent, a letter registering stop and a sliding locking key for the detent to lock or release the same and adapted also to move the detent into operative position.
13. In combination with the marking head, a detent therefor, a housing or pivoted support for said detent on which said detent has yielding movement, a letter registering stop and means for operating the detent from said stop, substantially as described.
14. In combination with the marking head, a pivoted detent, a locking key to move the said detent on its pivot, a sliding plunger, a lever pivoted at a point intermediate of its length, a connection between one end of said lever and the plunger, a connection between said lever and the locking key, means operated by the plunger for operating the detent to release it from the marking head, substantially as described.
15. In combination with the marking head, a detent pivoted intermediate of its length, a locking key bearing upon the rear arm of said detent and a letter registering stop for controlling the locking key, substantially as described.
16. In combination with a marking head

and letter registering stop, a detent intermediate pivoted and engaging the marking head, a locking key engaging the rear part of the detent and a releasing device engaging the front part of the detent, and both controlled from the letter registering stop, substantially as described.

In testimony whereof I affix my signature in the presence of two witnesses.

CELIA E. EVANS,
